UNITED STATES PATENT OFFICE.

ABRAHAM B. LANDIS, OF WAYNESBORO, PENNSYLVANIA.

GRINDING-MACHINE.

1,017,879.

Specification of Letters Patent. Patented Feb. 20, 1912.

Application filed July 7, 1909. Serial No. 506,356.

To all whom it may concern:

Be it known that I, ABRAHAM B. LANDIS, a citizen of the United States, residing at Waynesboro, in the county of Franklin and 5 State of Pennsylvania, have invented certain new and useful Improvements in Grinding-Machines, of which the following is a specification.

My said invention consists in various improvements in the details of construction of 10 grinding machines, whereby such a machine is provided for grinding cam-shafts, or shafts having a multiplicity of cam surfaces, such as are used in automobile construction, which will grind said cams accurately 15 of the shape desired and pass automatically from one cam to the next throughout the length of the shaft during the operation, all as will be hereinafter more fully 20 described and claimed.

Referring to the accompanying drawings which are made a part hereof and on which similar reference characters indicate similar parts, Figure 1 is a top or plan view of 25 a portion of a grinding machine embodying my said improvements, Fig. 2 a rear elevation of the same partly in section, Fig. 3 an end elevation, and Figs. 4, 5 and 6 detail views illustrating certain parts more clearly. 30 In said drawings the portions marked A represent the bed of the machine, B the carriage and C the slider.

In general the structure of the machine is or may be of any approved form, such as 35 shown in some of my former patents, embodying mechanism for traversing the carriage and driving the work, so well understood that detail illustration thereof is not necessary.

40 The bed is of suitable form to support the mechanism and has a table A' on one side thereof on which is mounted the head-stock A² and the foot-stock A³ for supporting the work-holding and driving devices. The 45 traversing carriage B is mounted on the opposite side of the bed A on suitable tracks and is adapted to be traversed longitudinally by any well known appropriate mechanism, not shown. The slider C is mounted 50 on the top of carriage B and is adapted to slide transversely thereof on a track c. The wheel-base C' is mounted on the top of slider C by means of inter-engaging tapered flanges c', c² on their respective edges. 55 The grinding wheel C² is mounted on a suitable shaft c³ journaled in bearings on

the forward end of said wheel-base in the usual manner. A hand wheel c⁴ is provided on the outer end of the operating shaft for operating the usual mechanism for feeding 60 the grinding wheel into the work, as is well understood.

Journalized in brackets A⁴ and A⁵ near the respective ends of the bed A is a pattern shaft 10 on which is formed the pattern of 65 the cams to be ground. Said shaft is connected by a sprocket chain-belt 11 mounted on a sprocket wheel 13 on a countershaft 12 with a sprocket wheel 14 on the shaft in the head-stock A². Said sprocket wheel 13 is 70 formed with a double face one of which has gear teeth 40 which mesh with the teeth of a pinion 15 on said shaft 10. A shaft 16 is journalized in bearings in the lower ends of arms C⁴ and C⁵, which project downwardly 75 from the rear end of slider C, and a wheel 17 is mounted on said shaft which is adapted to bear upon said pattern shaft. A rod 18 extends out from the rear side of carriage B with which it is connected by a 80 screw-threaded perforation at its inner end through a perforation in bracket C⁵ of the slider C and has a coiled spring 19 interposed between a shoulder in said bracket and a nut 20 on its outer end, and serves to 85 force said slider toward the work and hold the wheel 17 firmly against the pattern shaft 10 at all times. The tension of said spring 19 can be regulated by adjustment of the nut 20. A coiled spring 2 is interposed 90 between the inner side of arm or bracket C⁴ and a collar 22 on shaft 16. A similar spring 23 is interposed between the outer face of said arm or bracket and a collar 24 on the outer end of said shaft. A brake 25 95 consisting of a split ring is mounted on a pin 26 on the outer face of bracket A⁵ and surrounds a brake wheel 27 on the outer end of shaft 10. The inner face of said brake is preferably covered with leather or other 100 similar material 28. A screw 29 extends through the parallel flanges of the two parts by which it may be adjusted to clamp said brake wheel 27 more or less tightly as desired and insure that there will be no motion 105 of the pattern shaft except under the driving force of the gearing. Any slipping, or vibratory, or lost motion is thus guarded against.

In operation, the work W being driven by 110 suitable connection with the driving power through the pulley 30 on the outer end of

the head-stock spindle, the pattern shaft 10 is driven at a like speed through the sprocket belt 11, gear 13 on countershaft 12 and gear 15 on said shaft 10, which meshes with the 5 gear face of said gear 13. The cam patterns carried by shaft 10 being of corresponding form to those of the work W and driven at the same speed in the same direction the motion of the work and the pattern will be in 10 exact unison. Wheel 17 on shaft 16 carried by slider C bearing upon the face of the pattern said slider will be moved transversely as said pattern rotates and the grinding wheel C² thus maintained in operative relation to the face of the work at all times. The 15 parts being in position shown in Fig. 1, and the carriage B geared to move from left to right over the length of the cam-shaft constituting the work W the grinding wheel 20 C² will grind cam w of the perfect form corresponding to pattern cam p on shaft 10. Said work and pattern will rotate in unison and the grinding wheel and wheel 17 will move longitudinally in unison until said 25 grinding wheel has completely traversed the cam w when the side of wheel 17 may contact with the side of a concentric ring p' adjacent to cam p and hold said wheel until cam p has rotated to bring its highest point 30 into contact with wheel 17, which point will be in line with the face of part p'. The halting of wheel 17 has caused spring 23 to be compressed between collar 24 on shaft 16 so that as soon as cam p has rotated to bring 35 face of said wheel 17 in line with the face of part p' said spring will expand and draw said wheel onto said face which will hold slider C steady while grinding wheel C² is traversing the part of the work w' between 40 the cam faces. As the side of wheel 17 contacts with the side of the next cam p² of the pattern it is again halted until the portion of its face which is in line with the face of part p² is outward, when spring 23 will 45 again expand to pull said wheel forward onto the face of pattern p². The operation continues throughout the length of the work, when the direction of the travel of the carriage is reversed and the operation is re- 50 peated in the reverse direction, spring 21 operating between collar 22 and the inner face of bracket C⁴ to carry wheel 17 along from one part of the pattern to the other. The tension device consisting of the spring 55 19 bearing between a nut on rod 18, carried by carriage B, and a part of slider C serves to keep the slider forward and the grinding wheel in constant relation to the work at all times, while the brake 25 permits no motion 60 of shaft 10 except as positively driven by the gearing, thus guarding against backlash and vibration in the parts that could interfere with perfect results in the operation of the machine. The patterns on shaft 10 65 are made larger in diameter than the cam

being ground for the reason that stiffness in the parts is required to operate the slider C accurately, with its wheel base C' and wheel C² on top of it, but the throw of the cams is equal on both the pattern and the work. 70

Having thus fully described my said invention, what I claim as new and desire to secure by Letters Patent, is:—

1. A grinding machine for grinding cam shafts comprising a frame, work holding and driving mechanism, a traversing carriage, a slider thereon carrying the grinding wheel, a pattern shaft carrying a series of cams as patterns for the work to be ground, gearing for driving said pattern shaft uniformly 75 with the work, means for holding said slider yieldingly in contact with said pattern shaft, and means for moving said contact means from one pattern cam to the next, substantially as set forth. 80

2. A grinding machine for grinding cam shafts comprising a frame, work holding and driving mechanism, a traversing carriage, a slider thereon, a grinding wheel on said slider, a pattern shaft mounted on the frame 90 adjacent to a part of said slider and carrying cams of larger size but in shape a pattern of the work to be ground, and a yielding connection between said slider and said pattern, whereby the grinding wheel is held in 95 constant relation to the work, substantially as set forth. 85

3. A grinding machine comprising a pattern shaft with a series of cams thereon as patterns for the work and mounted adjacent 100 to the slider carrying the grinding wheel, a yielding connection between said slider and said pattern shaft, and means for moving said connection from one cam on said pattern shaft to the next, substantially as set 105 forth. 95

4. In a grinding machine, the combination of the frame, a traversing carriage thereon, a slider on said carriage, a grinding wheel on said slider, the work holding devices, a pattern shaft journaled on the frame adjacent to a part of said slider and carrying cams of same shape but larger in size than the work, gearing for driving the work and pattern shaft in unison, a contact wheel 110 carried on the slider and adapted to bear upon said pattern shaft, and a tension device interposed between a part of the slider and a part of the carriage for holding said wheel into constant contact with said pattern shaft 115 under yielding pressure, substantially as set forth. 120

5. In a grinding machine, the combination of a frame, a carriage, a slider thereon, a grinding wheel on said slider, the work holding devices, a pattern shaft adjacent to a part of the slider carrying the pattern for the work to be ground, gearing for driving the work and pattern shaft in unison, a contact wheel mounted on a shaft carried in, 125 130

bearings on the slider arranged to contact with said pattern shaft, said shaft being mounted to yield longitudinally as said wheel passes from one part of the pattern 5 to another, and means for holding said wheel yieldingly in contact with said pattern, substantially as set forth.

6. A grinding machine comprising a pattern shaft carrying the pattern for the work 10 adjacent to the slider, a contact device carried by said slider to bear upon said pattern, and means for holding said device on said pattern yieldingly in both a transverse and a longitudinal direction, substantially as set 15 forth.

7. In a grinding machine, the combination 20 of a frame, a carriage, work holding devices, a grinding wheel mounted on a slider, a pattern shaft adjacent to said slider, said slider, a contact wheel mounted on a shaft carried 25 by said slider, said shaft mounted to move longitudinally in its bearings, and tension devices to hold said shaft to normally move with said slider, substantially as set forth.

8. In a grinding machine, the combination 30 of the frame, a carriage, work holding devices, a pattern for the work on the frame, a slider carrying the grinding wheel, a contact wheel on a shaft carried by said slider adapted to bear upon said pattern, said shaft 35 mounted to slide longitudinally in its bearings, a collar fixed on said shaft on each side of one of said bearings, and a spring interposed between said bearing and each collar, substantially as set forth.

9. A grinding machine comprising a frame, a carriage, a slider, a grinding wheel thereon, work holding devices, a pattern shaft, gearing for driving the work and pat-

tern shaft uniformly, a contact wheel mounted 40 on a shaft, said shaft mounted to move longitudinally in bearings on said slider, means for holding said shaft to move normally with said slider, means for holding said contact wheel yieldingly to said pattern 45 shaft, and means for moving said shaft with the contact wheel longitudinally from one part of the pattern to another, substantially as set forth.

10. A grinding machine comprising a pattern shaft carrying the pattern for the work, a brake for holding said shaft against vibration or accidental movement, and the slider carrying the grinding wheel carrying a contact held to said pattern shaft under yielding pressure, substantially as set forth. 50

11. In a grinding machine, the combination, of the frame, the carriage, the slider, the grinding wheel thereon, the work holding devices, a pattern shaft carrying the pattern 55 for the work, a brake for holding said pattern shaft against accidental movement, gearing for driving said work and pattern in unison, a contact carried by the slider and held yieldingly to said pattern and adapted 60 to move longitudinally independent of the slider, and means for holding said shaft to move normally with said slider, substantially as set forth. 65

In witness whereof, I have hereunto set 70 my hand and seal at Washington, District of Columbia this 29th day of June, A. D. nineteen hundred and nine.
